(57) CLAIM

We claim the ornamental design for a smoking apparatus, as shown and described.

DESCRIPTION

FIG. 1 is an isometric view of a smoking apparatus.

FIG. 2 is a front elevation view of the smoking apparatus of FIG. 1.

FIG. 3 is a rear elevation view of the smoking apparatus of FIG. 1.

FIG. 4 is a right side elevation view of the smoking apparatus of FIG. 1.

FIG. 5 is a left side elevation view of the smoking apparatus of FIG. 1.

FIG. 6 is a top plan view of the smoking apparatus of FIG. 1; and,

FIG. 7 is a bottom plan view of the smoking apparatus of FIG. 1.

The dash-dot broken lines in the drawings immediately adjacent claimed surfaces represent boundaries of the claimed design and form no part of the claim, and all other broken lines depict portions of the smoking apparatus that form no part of the claimed design.
